UNITED STATES PATENT OFFICE.

LOUIS P. EISENBEIS, OF OTTUMWA, IOWA.

WICK-RAISER FOR MINERS' LAMPS.

No. 903,064.

Specification of Letters Patent.

Patented Nov. 3, 1908.

Application filed May 28, 1908. Serial No. 435,510.

To all whom it may concern:

Be it known that I, LOUIS P. EISENBEIS, a citizen of the United States, residing at Ottumwa, in the county of Wapello and 5 State of Iowa, have invented new and useful Improvements in Wick-Raisers for Miners' Lamps, of which the following is a specification.

My present invention relates to improvements in wick raisers for lamps especially 10 of the type used by miners, and it has for its object primarily to provide an improved device of this character that is simple in construction so that it may be manufactured 15 cheaply and is not liable to get out of order, and wherein the wick raiser is so mounted with respect to the wick tube that it will permit the introduction of a wick without interfering therewith, and which will not 20 permit the oil to escape from the wick tube except at the top thereof at which point the flame is located.

To these and other ends, the invention 25 consists in certain improvements, and combinations and arrangements of parts, all as will be hereinafter more fully described, the novel features being pointed out particularly in the claims at the end of the specification.

30 In the accompanying drawing: Figure 1 is a perspective view of a miner's lamp equipped with a wick raiser constructed in accordance with my present invention, a portion of the wick tube being broken away to 35 illustrate the wick raiser; Fig. 2 is a plan view of the lamp shown in Fig. 1; Fig. 3 represents a vertical section of the wick tube; Fig. 4 represents a transverse section of the wick tube as shown in Fig. 3; Fig. 5 40 is a perspective view of the inner wick tube constructed to receive the wick raiser; and Fig. 6 is a perspective view of the wick raiser removed from the tube.

Similar parts are designated by the same 45 reference characters in the several views.

Wick raisers constructed in accordance 50 with my present invention are capable of being readily applied generally to miners' lamps of various constructions. In the accompanying drawing, I have shown the invention applied to an ordinary miner's lamp having an inner wick tube and a surrounding cooling tube. It will be understood, 55 however, that the drawing illustrates one specific embodiment only of the invention, and that certain changes in the specific con-

struction or modifications in the relative arrangements of the parts, may be made in order that the invention may be applied to the best advantage in each particular case. 60

In the present instance, the lamp to which the invention is applied comprises a body portion or receptacle 1 which is adapted to contain a suitable quantity of oil, it being provided with the usual top 2 and a supporting hook 3. Attached to the body portion of the lamp is a wick tube 4 and, if so desired, an outer tube 5 may be provided which surrounds the wick tube and provides an annular cooling space. It is obvious, however, 70 that this outer tube may, if preferred, be omitted. The wick tube is formed with a longitudinal or axially extending groove or channel 6 which extends from the top of the tube downwardly to a given point, the 75 groove or channel in the present instance being formed integrally with the wick tube by crimping or rolling a portion of one of its walls into substantially the form of a second smaller tube, and by forming this groove or 80 channel integrally with the wick tube, the use of rivets or of solder which would be liable to melt, is obviated. The lower end of this groove or channel merges into an outwardly expanded portion 7 which is also 85 preferably formed integrally with the wick tube and is of segmental form so as to partially surround the tube, this outwardly expanded portion being of such a length with respect to the axis or length of the tube as to 90 permit a sufficient longitudinal movement of the wick raiser. This wick raiser shown in the present instance is composed of a wire 95 which is doubled longitudinally so as to form an intermediate portion 8 which is adapted to extend over the upper edge of the outer tube 5, and the ends of the intermediate portion form a pair of substantially parallel arms 9 and 10, the arm 9 being adapted to enter the longitudinal groove or channel 6 100 of the wick tube and is provided on its lower end with a laterally bent segmental wick engaging jaw 11 which is adapted to enter the outwardly expanded portion 7 of the wick tube and to operate longitudinally therein as 105 the wick raiser is elevated or lowered. The other arm 10 of the wick raiser extends downwardly at the outer side of the tube 5 and is preferably provided at its lower end with a rolled portion or other suitably 110 formed part which is adapted to provide a handle 12 by means of which the wick raiser

may be readily manipulated. The wick engaging jaw 11 of the wick raiser is preferably serrated or provided with relatively sharp teeth at its inner side, as shown, wherefore it may obtain an effective hold upon that portion of the wick with which it engages.

Normally, the curved or segmental jaw of the wick raiser occupies a position within the outwardly expanded portion 7 of the wick tube, the inner or serrated surface of this jaw lying substantially flush with the interior bore of the wick tube, as shown in Figs. 1, 3 and 4. While the wick raiser is in this position, a wick may be readily inserted into the wick tube from either end, preferably from the lower end. After the wick tube has been inserted, the wick may be raised from time to time as occasion may require by first turning the wick raiser by means of the handle 12 so as to rotate it about the arm 9 as an axis, the groove or channel 6 serving as a bearing. Such a rotation of the wick raiser will move the serrated jaw 11 thereof inwardly thereby obtaining an effective hold upon the wick, and while the wick raiser is held in this position, it is elevated, such a movement of the wick raiser causing the wick to be fed toward the upper end of the wick tube, and when it is desirable to again raise the wick, the wick raiser is rotated so as to carry the serrated jaw thereof into the outwardly expanded portion 7 of the wick tube, and while it is thus contained in this portion of the wick tube, the wick raiser may be depressed, thereby passing the wick freely and without engaging it so as not to carry the wick downwardly. After the wick raiser has been sufficiently lowered, it may then be rotated so as to carry the serrated jaw again into engagement with the wick, and by lifting the wick raiser while the edge thereof is thus engaged with the wick, the latter may be sufficiently raised. In the present instance, the wick tube, as previously stated, is surrounded by an outer tube which serves not only to effect a cooling of the wick tube, but it also conceals the outwardly projecting groove or channel and the expanded portion into which said channel leads so that the lamp presents a neat appearance. It will be obvious, however, that this outer tube may, if so desired, be omitted, in which case the wick tube and its co-operating raiser will be complete in itself. As the groove or channel and the outwardly expanded portion which receive the wick raiser are formed integrally with the wick tube and do not perforate the same, it will be obvious that leakage of oil below the top of the wick tube is impossible.

A wick raiser constructed in accordance with my present invention is simple in construction and may be manufactured cheaply, and by applying it to the wick tube in the manner shown, it is possible to readily form

the wick tube so as to accommodate the wick raiser with the greatest facility, the outwardly projecting channel and expanded portion being preferably formed by means of dies so that the manufacture of these parts is inexpensive, and in practice, the wick raiser serves to effectually raise the wick from time to time as may be necessary. Moreover, by applying it to the wick tube in the manner hereinbefore described, leakage of oil is effectually prevented, and the necessity of attaching additional parts to the wick tube, such for instance as by rivets or soldering, is obviated.

I claim as my invention:—

1. A device of the class described comprising a wick tube provided with an outwardly expanded portion, and a wick raiser having a wick engaging portion reciprocable longitudinally of the wick tube and movable transversely into and out of the outwardly expanded portion of the wick tube to engage or disengage a wick therein. 80

2. A device of the class described comprising a wick tube having an outwardly expanded portion, and a wick raiser comprising a depending reciprocable arm having its lower end bent laterally to form a wick engaging jaw rotatable into and out of engagement with the wick and reciprocable longitudinally of the wick tube said jaw being housed in said outwardly expanded portion of the wick tube. 90

3. A device of the character described comprising a wick tube having a portion below its upper edge imperforate and expanded outwardly, and a wick raiser movable longitudinally of said tube and having a wick-engaging portion which is capable of normally lying within said outwardly expanded portion of the tube to provide a free passage for the wick, said wick-engaging portion being movable transversely in said expanded portion to engage and disengage the wick. 100

4. A device of the class described comprising a wick tube provided with an outwardly expanded portion, and a wick raiser having an arm extending downwardly from the top of the wick tube and provided with a laterally bent wick engaging jaw which is curved to conform substantially to the curvature of the wick tube and is rotatable into and out of the laterally expanded portion of the tube to engage or disengage the wick. 115

5. A device of the class described comprising a wick tube, and a wick raiser composed of a strip of wire doubled to form an inner arm which extends longitudinally of the wick tube and is provided with a transversely arranged wick engaging portion adapted to move transversely of the tube to engage or disengage the wick and is reciprocable longitudinally thereof, the wick raiser 125

being also provided with an outer arm which extends downwardly from the upper edge of the wick tube and is arranged wholly exteriorly of the wick tube and adapted to 5 serve as a handle for the manipulation of the wick raiser.

6. A miner's lamp involving a wick tube provided with an outwardly expanded portion and a longitudinal groove or channel 10 extending downwardly from the top of the wick tube and entering the outwardly expanded portion thereof, and a wick raiser having a portion operable from the exterior of the wick tube and provided with an arm 15 which extends downwardly through the longitudinal groove or channel of the wick tube and has its lower end bent laterally to provide a serrated wick engaging jaw which is adapted to be contained within the outwardly expanded portion of the wick tube, 20 said jaw being rotatable to and from engagement with the wick about the said arm of the wick raiser as an axis and being reciprocable longitudinally of the tube.
- 25 7. A miner's lamp embodying a wick tube having a portion of the metal thereof ex-

panded outwardly and having a longitudinal groove or channel formed also integrally with the tube and extending from the top thereof into said outwardly expanded portion, and a wick raiser comprising a strip of wire doubled longitudinally, one arm thereof extending downwardly through said longitudinal channel and provided with a laterally bent end which forms a transversely 35 curved wick engaging jaw which is adapted to operate in the outwardly expanded portion of the tube, said jaw being rotatable to and from engagement with the wick about the said arm as an axis and is reciprocable 40 longitudinally of the tube, the other end of the wick raiser forming an arm arranged exteriorly of the wick tube and serving as a handle for the manipulation thereof.

In testimony whereof I have hereunto set 45 my hand in presence of two subscribing witnesses.
